US00D451385B1

(12) **United States Design Patent** (10) Patent No.: **US D451,385 S**
Bryan et al. (45) Date of Patent: ** Dec. 4, 2001

(54) **CONTAINER**

(75) Inventors: **Denis Bryan; Richard Bicknell; Gareth Pugh; Kate Stapleton**, all of London (GB)

(73) Assignee: **Kimberly-Clark Limited (GB)**

(**) Term: **14 Years**

(21) Appl. No.: **29/130,689**

(22) Filed: **Oct. 6, 2000**

(30) **Foreign Application Priority Data**

Jun. 4, 2000 (GB) 2092011

(51) LOC (7) Cl. **09-03**

(52) U.S. Cl. **D9/423; D9/430; D9/431**

(58) **Field of Search** D9/420-424, 430, D9/431, 432, 337, 414; 206/278, 286, 287, 292, 295, 299; 229/103.2, 103.3, 106, 108, 112, 113, 114, 116.1, 122, 230-232, 229, 160.1, 160.2, 125.08, 124
